Primary Examiner — Paula Greene(74) *Attorney, Agent, or Firm* — Taft Stettinius & Hollister LLP(57) **CLAIM**

We claim the ornamental design for a cabinet and/or drawer knob, as shown and described.

DESCRIPTION

FIG. 1 is a perspective view of a cabinet and/or drawer knob of the present claimed design;

FIG. 2 is a side elevation view of the cabinet and/or drawer knob shown in FIG. 1, the other side elevation views being identical thereto;

FIG. 3 is a top plan view of the cabinet and/or drawer knob shown in FIG. 1; and,

FIG. 4 is a bottom plan view of the cabinet and/or drawer knob shown in FIG. 1.

Features shown in broken lines in the drawing form no part of the claimed design.
